UNITED STATES PATENT OFFICE.

HUGH McC. BARR AND GEORGE EDGAR, OF PENSACOLA, FLORIDA.

STEAM BLOWER.

Application filed May 2, 1921, Serial No. 465,983. Renewed December 10, 1923.

To all whom it may concern:

Be it known that we, HUGH M. BARR and GEORGE EDGAR, citizens of the United States, and residents of Pensacola, in the 5 county of Escambia and State of Florida, have invented certain new and useful Improvements in Steam Blowers, of which the following is a specification.

This invention is a steam blower for cleaning ashes or cinders or other products of combustion, etc., from the combustion chamber or back connection of furnaces and particularly marine and stationary boilers.

It is well known that from continued use, 15 there collects in the back connection or chamber of steam boilers and particularly marine and stationary boilers, ashes, cinders and other foreign matter or products of combustion which tend to clog up the boiler 20 tubes and interfere with combustion, but up to this time, no efficient means has been provided for effectively cleaning out said back connection or combustion chamber without scraping the latter or getting into the furnace fire box and removing such matter 25 through the feed door thereof.

This invention contemplates a steam blower adapted to be arranged in the back connection or combustion chamber of marine 30 and stationary boilers in particular and which has connection with a source of steam supply through the medium of the boiler head or chest, or with the main or auxiliary steam line, as shall be found most convenient, the pipe or supply connection having 35 means for controlling the supply of steam to the blower proper so that the loose ashes and cinders or any other foreign matter lodging in the connection will be blown out 40 through the boiler or fire tubes and flue or smoke stack, the device being especially designed for use in connection with return draft boilers, of the fire tube type.

It is therefore a further and important 45 object of the invention to provide a simple and improved steam blower for boilers which may be readily and conveniently installed, and by which the cleaning of the back connection or combustion chamber may 50 be particularly and effectively carried out, and which will so discharge the steam as to act upon all surfaces and lodging places for such foreign matter or products of combustion so as to effectively clean the same and 55 result in a better draft and more efficient operation of the furnace.

Other and further objects of our invention will become readily apparent to those skilled in the art, from a consideration of the following description when taken in conjunction with the accompanying drawings, 60 wherein:

Figure 1 is a vertical longitudinal sectional view of a furnace or boiler equipped with an improved steam blower constructed 65 in accordance with the invention, and

Figure 2 is a transverse vertical sectional view of the device, the section line being indicated at 2-2 of the drawing.

Referring to the drawings in detail, in 70 which like reference characters designate corresponding parts throughout the several views, there is shown a conventional form of furnace or boiler as used in connection with marine or stationary heating plants, 75 the same being designated at 10 and indicated as of having a return draft. The steam chest or head of the boiler proper is designated at 11. The fire box is designated at 12, and below the grate 13 is provided the 80 ash pit 14, the latter having a clean out door 15 and the fire box being provided with the door 16 in the front portion 17 of the furnace in the usual manner. In rear of the fire box and ash pit or box, and thus at the 85 back end of the grate is arranged a vertical transverse division wall 18 extending between the sides of the fire box and extending from the bottom wall of the latter toward but terminating short of the boiler tubes or 90 flues 19 of the boiler proper, as shown at 20, the water in the boiler circulating around said tubes in the usual way.

Between the division wall 18 constituting the bridge wall arch of the furnace and the 95 back wall 21, there is provided a back connection or combustion chamber 22 in which loose ashes, cinders, waste products of combustion or other foreign matter will become collected or lodged during the continued use 100 of the furnace, the draft being rearward through either of said doors, and over said division wall 18, then through the boiler tubes 19 and out the flue or smoke stack 23 which latter is arranged at the front of the 105 furnace. In this manner, the heat from the products of combustion will effectively heat the water and raise the same to the proper temperature resulting in the generation of steam.

The steam thus generated is employed in 110 connection with the cleanout device or blow-

er, which embodies a perforated plate, mushroom head or cast iron head, as indicated at 24, the same being arranged within the circular bottom portion of the back connection 5 or combustion chamber 22 as clearly shown in Figure 2 of the drawing and supported in spaced relation by means of feet or brackets 25. As shown, this foraminous or perforated blower device is of semi-circular 10 cross section, the flat face extending diametrically and being disposed at the bottom and the semi-circular curved surface being exposed uppermost, and provided with a series of perforations as indicated at 26 of suitable 15 size, preferably about $\frac{1}{8}$ ths of an inch in diameter. One end of the blower head or pipe is closed, as indicated at 27 and the opposite end is arranged to afford connection with a steam supply pipe 28, which latter 20 may extend from a suitable source of supply, such as a boiler or header proper, or may constitute the main or auxiliary steam line.

As indicated, this steam line or pipe is provided with an inlet 29 leading from the 25 steam chamber of the boiler and extending around the outside of the furnace to a point adjacent to the end of the blower head or pipe 24, where it is extended in water and steam tight connection through the walls 10 and 21 for connection to the adjacent end 30 of said head or pipe as indicated at 30, suitable pipe fittings being employed, as is very common in the art. However, the connection is made detachable in order to facilitate 35 the application of the device or disconnection thereof for cleaning, renewal or repair. In the pipe line, is interposed a globe or other type of control valve 31, in order that the supply of steam to the blower 40 proper may be regulated and controlled so that the device may remain inoperative while the furnace is in use, or opened to in turn drive steam into the blower in the back connection which will result in the discharge 45 thereof through the apertures or holes in the lower head or pipe, in the manner particularly indicated in Figure 1 of the drawings, so as to discharge said steam into all crevices and effectively loosen and remove waste 50 products of combustion and other foreign matter accumulating therein. Obviously, when the steam is turned on, the loose ashes and cinders will be blown from the back connection chamber out through the tubes 55 and smoke stack, the course of the jets of steam and the products of combustion and foreign matter carried along therewith when the furnace is in use being that indicated by the arrows. Of course, whether the furnace 60 is in use or not, the loose ashes and cinders which have become collected or lodged in the back connection will also be effectively removed, taking the same course and thereby serving to thoroughly clean out the boiler

to produce a more effective draft and increased capacity.

While we have described the device as applied to a marine or stationary type of boiler in which the draft is rearward over the fire box and bridge wall arch, forming a division wall at the rear end of the fire box, and grate, as well as the ash box or pit, and in which the return draft is forward through the boiler tubes or flues, it is to be understood that the blower and the principles embodied in its application and use, may be employed in connection with other types of boilers with equal facility and that we do not restrict ourselves to the specific type of boiler shown. It is also to be understood that the specific form of blower head may be modified both as to position and form, and that the same may be of circular, semi-circular or other cross sectional shape, so long as it is provided with perforations through which the dry steam may be discharged under pressure for carrying out the objects of the invention. In addition, the blower head may be connected directly to the steam space of the boiler, to any one or more headers or superheaters that may constitute the main or auxiliary steam line, using either of these lines as will be found most convenient in accordance with the particular type of furnace or boiler to which the invention is applied, reference being had also to the location of the valve for controlling the supply to the blower head as described.

However, when the steam blower is not 100 working and is shut off, the valve 31 being closed, provision is made for the circulation of cold air through the main steam line pipe below said valve 31 and through the blower head 24 consisting of a valve 32 having a 105 short pipe 33 leading therefrom and open to the atmosphere, thus permitting a circulation of cold air through the pipe and blower head in order to keep the same cool and prevent it from burning out. Also, by reason of the draft created within the furnace chamber an additional supply of oxygen will be drawn in to facilitate combustion, especially in the back connection and thereby eliminate considerable waste.

In view of the foregoing, it is thought that the operation of the device will be readily understood, and in view of its simplicity and practical value that it will readily commend itself to those skilled in the art.

Having thus described our invention what we claim as new and desire to secure by Letters Patent is:

A cleanout device of the character described comprising in combination with the 125 back connection or combustion chamber of a furnace or boiler, a blower head mounted upon the bottom of the back connectin or

combustion chamber in spaced relation thereto and being curved to conform to the curvature of the bottom wall, a conduit for conducting steam from a source of supply to the blower head, a valve located exteriorly of the furnace or boiler for controlling the flow of steam through the conduit, and a valved intake connection for the conduit between the valve and the blower head, whereby a cleaning fluid may be supplied to the blower head when desired.

HUGH McC. BARR.
GEORGE EDGAR.
